TYPOGRAPHICAL CASTING MACHINE

George A. Doxey, Staten Island, N. Y., assignor
to Mergenthaler Linotype Company, a corpora-
tion of New York

Application January 7, 1932. Serial No. 585,205

20 Claims. (Cl. 199—26)

This invention relates to typographical casting machines, such as linotype machines of the general organization represented in U. S. Letters Patent to O. Mergenthaler, No. 436,532, wherein circulating matrices are released from a magazine in the order in which their characters are to appear in print, and then composed in line, the composed line transferred through an intermediate channel into a vertically movable first elevator 5 which carries the line to a slotted mold, the mold filled with molten metal to form a slug or linotype against the matrices which produce the type characters thereon, and the matrices thereafter returned through a distributing mechanism to the 10 magazine from which they started.

While these machines are capable of handling a variety of matrix fonts, it is frequently desirable to cast a few lines from some particular font or fonts not carried at the time in the machine, and 20 in such instances it is customary either to compose the matrices by hand in the assembler or to employ a special form of hand stick in which there may be composed by hand matrices of regular or machine-composed size or matrices too large or otherwise not intended for machine composition.

The present invention contemplates certain improvements in the machine which will permit hand-composed matrix lines to be handled with much greater ease and facility than heretofore. 30 To this end, specifically, the structure of the intermediate channel is made to include a detachable section which is provided with means for converting it into a hand stick when detached. In its converted state, the detached section is 35 capable of handling not only matrices of the different sizes required but in addition the regular linotype spacebands, so that a line composed therein may be justified in the same way as if composed directly in the machine.

40 After a line has been composed in the detached converted section, the latter is reapplied to the machine and then restored to its original or normal condition, it being understood that the composed line will then be supported in the intermediate channel in the regular way. The line is now transferred by hand into the first elevator which presents it to the line clamping, justifying and casting devices in the regular way, the line being handled precisely as if it were composed 45 in the machine itself and forwarded automatically.

50 After the casting of the slug, the machine is allowed to continue its normal operation up to the point where the matrices have been transferred from the first elevator onto the second

elevator bar and the latter carried upwardly for a slight distance above the upper transfer channel, the spacebands at the time remaining in said channel. At this point, the operation of the machine is manually arrested, and the matrices stripped off the second elevator bar by hand. The machine is then restarted and allowed to complete its cycle of operation, the spacebands thereby being restored automatically to the spaceband magazine of the machine. Of course, if 55 desired, the spacebands could be removed by hand from the upper transfer channel at the time the machine is brought to rest for the hand removal of the matrices.

In the accompanying drawings, the invention 70 has been shown merely in preferred form and by way of example and as applied to a commercial linotype machine, but obviously many changes and variations may be made therein and in its mode of application which will still be comprised 75 within its spirit. It should, therefore, be understood that the invention is not limited to any specific form or embodiment except in so far as such limitations are specified in the claims.

Referring to the drawings:

Fig. 1 is a front view of a portion of a linotype machine equipped with the present improvements;

Fig. 2 is a top plan view of the intermediate channel with a line of hand composed matrices 85 positioned therein, the receiving end of the first elevator being shown in section;

Fig. 3 is a front elevation of the parts shown in Fig. 2;

Fig. 4 is an end view of the intermediate channel showing the matrix retaining bar and end walls of the detachable section or hand stick thrown back into their inactive position;

Fig. 5 is a vertical section taken on the line 5—5 of Fig. 4 showing a composed line supported 95 in the hand stick;

Fig. 6 is an end view of the hand stick detached showing a composed matrix line supported therein; and

Fig. 7 is a detail face view of a regular two-letter matrix.

In the normal operation of the machine, the matrices X and spacebands Y (Fig. 1) are released from their respective storage magazines X¹ and Y¹ by the manipulation of a keyboard (not shown) and are delivered, one at a time, to the assembler A wherein they are stacked in line under the influence of a star wheel a. When the line is completely composed, the assembler is raised into registry with the intermediate channel 105 110

B and trips the delivery slide C, which thereupon transfers the line from the assembler through said channel and into the vertical movable line transporter or first elevator D. By this, the active stroke of the delivery slide, the machine cycle of operation is inaugurated and the last matrix of the composed line is located immediately behind a pair of spring retaining pawls d (Fig. 2) arranged at the receiving end of the first elevator. The elevator now descends to present the composed line to the mold, where it is properly justified between the usual clamping jaws preparatory to the casting of the slug. After the slug casting operation, the first elevator D is raised to its uppermost level and the line transferred therefrom into the upper transfer channel E (Fig. 1), the matrices at this time being caused to engage the second elevator bar which carries them upwardly for distribution into their magazine X¹, and the spacebands being left behind in the channel E and later returned to their magazine Y¹.

The matrices X, one of which is shown in detail in Fig. 7, are representative of the regular two-letter variety, while the matrices X², shown in Figs. 5 and 6, are representative of the head-letter or display variety, the former being provided with two superposed characters x of small size and the latter with but a single character x¹ of much larger size. The individual matrices of both varieties are formed as usual with the upper and lower projecting ears x², x³, and the V-shaped distributing notches x⁴.

The spacebands Y are of regular construction, each comprising the relatively fixed wedge-shaped member y¹ and the movable longer wedge-shaped member y², these members being slidably connected together so that the longer members may be driven upwardly to expand the composed lines in effecting justification. The shorter members y¹ of the spacebands Y (see Fig. 5) are formed at their upper ends with V-shaped clearance notches y³ corresponding to the distributing notches x⁴ of the matrices, and also with projecting ears y⁴ by means of which the spacebands are sustained during their circulation through the machine.

In the use of the two-letter matrices X, it is customary to compose them at an upper level in the assembler A to bring their lower characters into casting position, or at a lower level therein to bring their upper characters into casting position; whereas, in the use of the head-letter matrices X², it is customary to compose them at the lower level in the assembler and to arrest the first elevator in a slightly raised position with reference to the mold so as to bring the single characters x¹ of these matrices into proper casting position.

As best shown in Fig. 4, the structure of intermediate channel B includes mainly, a front side wall B¹ and a rear side wall B², these two walls being screwed together in predetermined spaced relation and secured to the front of the machine frame. To give the individual matrices and spacebands of composed lines the required support in their passage through the channel B, it is provided with three pairs of superposed horizontal rails b¹, b², b³. The uppermost pair of rails b¹ is devoted to the spacebands Y, being arranged to cooperate with the projecting ears y¹ thereof, while the intermediate and lowermost pairs of rails b² and b³ are devoted to the matrices. The rails b² are adapted to cooperate with the upper

projecting ears x² of the matrices if composed at the lower level in the assembler A, and the rails b³ are adapted to cooperate with the lower projecting ears x³ of the matrices if composed at the upper level in the assembler. The intermediate rails b² are therefore common to both the regular matrices X and the display matrices X², while the lowermost rails b³ are individual to the two-letter matrices X.

The several pairs of rails b¹, b², and b³, are formed directly on front and rear anti-wear plates B³ and B⁴, the inner faces of which are grooved longitudinally at b¹⁰ and b¹¹ to produce the uppermost and lowermost rails b¹ and b³ respectively, and recessed at b¹² to produce the intermediate rails b². Ordinarily, these wear plates B² and B³ are secured to the respective side walls B¹ and B² of the intermediate channel and thus constitute permanent parts of the machine. According to the present invention, however, the front plate B³, for reasons presently to appear, is fastened to a removable section F of the front wall B¹, which latter, as shown best in Figs. 4 and 5, is cut away at the top or made lower than usual to accommodate the said section.

In the preferred embodiment illustrated, the section F is detachably connected to the wall B¹ by means of latch pins or detents B⁵, and is sustained thereon in a truly vertical position by a pair of banking screws b⁴. The latch pins B⁵ (Fig. 3) are slidably mounted in suitable housings B⁶ and are arranged to engage in corresponding apertures f (Fig. 4) formed in lugs F¹ projecting from the front face of the removable section F near the opposite ends thereof. Each latch pin B⁵ is held in its active or locking position by a compression spring b⁵ and is retractable at will, to break its engagement with the corresponding aperture f, by means of a finger grip or handle b⁶ projecting forwardly from the pin through an elongated slot b⁷ formed in the associated housing B⁶.

The banking screws b⁴ are mounted in the upper edge of the front wall B¹ behind the latch pins B⁵ and are arranged to engage the lower edge of the section F when it is attached to the channel B. A flat spring B⁷, pivoted at its lower end to the front wall B¹ and reacting against the section F, tends to press the latter rearwardly about the pins B⁵ as a fulcrum and maintain it resiliently engaged with the banking screws b⁴. With this arrangement, the section F may be instantly disconnected from the channel B for removal by merely swinging the spring B⁷ downwardly out of engagement with the section F to the position indicated by the dotted lines in Fig. 3, and then withdrawing the latch pins B⁵ from engagement with the lugs F¹.

Considered as a separate and independent element, the section F in size and weight is suitable for use as a hand stick, as intended, and in adapting it for such use, it is provided with a pair of fingers F² between which a line of matrices and spacebands may be composed as well as with a bar F³ for holding the composed line in place upon the supporting rails.

In this instance, the bar F³ is V-shaped and arranged to engage in the V-shaped notches formed in the upper ends of the matrices and spacebands, being hingedly connected to the section F through the medium of a pair of integral arms F⁴, which latter are mounted on cross pins f¹ and guided in vertical cuts or notches B⁸ formed in the upper edge of the plate B³. The notches

⁵ B⁸ present each a vertical portion b⁸ and an inclined or beveled portion b⁹, which serve respectively through their engagement with the arms F⁴ to locate the bar F³ in its active and inactive positions (compare Figs. 6 and 4).

¹⁰ The fingers F² (as shown in Fig. 5) are attached to the opposite ends of the bar F³ in order that they may be carried out of engagement with the matrix line as the bar is swung to its inactive position, this latter operation being effected manually after the section F has been restored and locked in place on the structure B. However, to permit angular adjustment of the fingers, as may be desired during composition, they are pivoted ¹⁵ to the bar F³ by screws f² which exert sufficient friction on the fingers to maintain them yieldingly in any position to which they may be moved. The arms F⁴ of the bar F³ may likewise be maintained under friction by their pivot pins f¹ for the sake of convenience in handling the stick and also to facilitate composition of a matrix line between the fingers F².

²⁰ While the hand stick above described (see Fig. 6) presents but a single side wall B³, the matrices and spacebands will be properly supported and held in place thereon both during and after composition. Thus, the inner face of the plate B³ (as may be noted in Fig. 6) is shaped to fit between the upper and lower projecting ears of the matrices and hence will restrain them against endwise displacement and keep them at all times engaged with the rail b², it being understood that during composition of a line the section F will be held normally at a backward inclination or in a semi-horizontal position. The spacebands during composition will be kept in line by the engagement of their projecting ears y¹ in the groove b¹⁰ of the plate B³ and, if need be, may be held against edgewise displacement by the bar F³, which can be set in the position indicated by the dotted lines in Fig. 6. When composition is completed and the line receives support at both ends by the fingers F², the bar F³ is moved to the position shown by the full lines in Fig. 6, where it fits snugly within the V-shaped notches x⁴ of the matrices and the corresponding notches y³ of the spacebands and thereby serves to hold the line in place upon the plate B³, preventing any edgewise displacement of the matrices or spacebands or lateral displacement of the line as a whole. It hardly needs to be stated that when the matrices are supported on the rail b², their V-shaped notches will be aligned with those of the spacebands, so that the bar F³ may function in the manner just stated. In the use of the section F as a hand stick, matrices will not be composed on the lower rail b³, and its presence could be omitted altogether, were it not for the fact that the section, when not employed as a hand stick, must match up with the rear wall of the intermediate channel in handling machine-composed matrices standing at different levels.

⁶⁵ According to the foregoing improvements, whenever it is desired to convert the movable section F of the intermediate channel B into a hand stick, it is first detached in the manner before described, and the bar F³ then swung over to the position indicated by the dotted lines in Fig. 6, thus permitting matrices and spacebands to be inserted beneath it into engagement with the rails b¹ and b² of the plate B³. The finger F² at the left is now adjusted so as to support the matrices facewise as they are stacked in line, and when the line has been completely composed, the

bar F³ is pushed down to the full line position shown in Fig. 6. The finger F² at the right, which determines the length of the line, may be placed in position during composition or swung down after the last matrix has been composed, as may be found most convenient. With both fingers F² and the bar F³ in place, the line is firmly supported in all directions, and the whole unit may therefore be handled with all convenience and safety.

⁸⁰ In applying the section F with the composed line to the machine, the latch pins B⁵ are retracted within their respective housings to clear the lugs F¹, and the section then pushed rearwardly on the banking screws b⁴ to carry the projecting ears y⁴ of the spacebands and the upper projecting ears x² of the matrices into engagement with the rails b¹ and b² of the stationary rear wall B⁴ of the channel B (see Fig. 4). The latch pins B⁵ are now released and allowed to snap into the aligned apertures of the lugs F¹, and the retaining spring B⁷ is turned upwardly in front of the stick to hold it in upright position as determined by the banking screws b⁴. The only remaining operation required to prepare the line for transfer from the channel B into the first elevator D is that of swinging the bar F³ and the attached fingers F² forwardly out of engagement with the line to the idle position shown by the full lines in Fig. 4. In this operation, the fingers F² may engage the front face of the rear plate B⁴ but, being pivoted to the bar F³, they will yield about their pivotal axes and finally assume a horizontal position out of the way of the composed line as the arms F⁴ of the bar approach the bottom walls of the notches B⁸.

⁹⁰ The transfer of the composed line is effected manually, and the proper position thereof as it comes to rest in the first elevator D is determined by the spring retaining pawls d, the operator being able to feel the action of these pawls as the last matrix of the line is pushed past them. The operation of the machine is now started by means of the clutch control handle common to all commercial linotype machines, and the composed line is handled automatically in the customary way, the line being "locked up" and justified and a slug cast therefrom in the well known manner. As the cycle proceeds and the transporter rises into registry with the upper transfer channel E (Fig. 1), the matrices of the line are transferred onto the second elevator bar (not shown), from which they are stripped by hand after the operation of the machine is manually arrested, and the spacebands are delivered to the storage magazine Y¹ or removed by hand from the transfer channel. Of course, the matrices could be "run pi" if desired, in which case the machine would be allowed to complete its cycle of operation without interruption.

¹⁰⁰ Having thus described my invention, what I claim is:

¹¹⁵ 1. In or for a typographical casting machine adapted to handle matrices and spacebands formed with projecting ears, a hand stick including, in combination, means for supporting the matrices and spacebands of a composed line by their projecting ears at one side only of the line, and means for holding the line against displacement on the supporting means.

¹²⁰ 2. In or for a typographical casting machine adapted to handle matrices and spacebands formed with projecting ears, a hand stick comprising a single side wall, parallel rails formed on the side wall for supporting the individual

matrices and spacebands of a composed line by their projecting ears, and means for holding the line against displacement on said rails.

3. A hand stick as specified in claim 2, characterized by the fact that the said holding means include a bar arranged to cooperate with both the matrices and spacebands for restraining the composed line against lateral displacement, and a pair of end walls for restraining the line 10 against endwise displacement.

4. A hand stick as specified in claim 2, characterized by the fact that the matrix supporting rail is formed on a plate which fits against the contiguous edges of the matrices between their 15 upper and lower projecting ears so as to support them edgewise and maintain them individually against longitudinal displacement on the said rail.

5. A hand stick as specified in claim 2, characterized by the fact that the spaceband supporting rail is formed by a groove extending longitudinally of the side wall of the stick and wherein the 20 projecting ears of the spacebands engage.

6. In or for a typographical casting machine 25 adapted to handle matrices and expandible spacebands, a hand stick comprising a single side wall, means for supporting the matrices and spacebands of a composed line vertically thereon, a bar hinged to the side wall for preventing lateral 30 placement of said line, and a pair of fingers mounted on the bar for sustaining the line endwise.

7. A hand stick as specified in claim 6, characterized by the fact that the hinged bar therein 35 referred to is arranged to engage notches formed in the upper ends of the matrices and spacebands.

8. In a typographical casting machine, the combination with means for supporting the matrices and spacebands of a composed line in casting 40 position, of a channeled structure from which said line is transferred to the supporting means, said structure including a detachable section adapted for use as a hand stick when detached.

9. In a typographical casting machine, the 45 combination with means for supporting the matrices and spacebands of a composed line in casting position, of a channeled structure from which said line is transferred to the supporting means, said structure including a detachable section, 50 and means mounted on the section for converting it into a hand stick when detached.

10. A channeled structure as specified in claim 9, characterized by the fact that the detachable section is formed with means for supporting the 55 matrices and spacebands vertically by their projecting ears, and that the converting means therein referred to consists of a bar movable into engagement with a composed line for holding it against lateral displacement on the supporting means, and a pair of fingers movable into position to act as end walls for the composed line.

11. In or for a typographical casting machine 60 adapted to handle matrices and expandible spacebands formed with projecting ears, a channel structure comprising a detachable section convertible at will into a hand stick, said stick including a pair of end walls, a single side wall, rails formed on the side wall for supporting the 65 matrices and spacebands of a composed line by their projecting ears, and a bar movable into engagement with the line for holding it in position on said rails.

12. In or for a typographical casting machine, 70 a channel structure comprising front and rear

side walls for supporting the matrices and spacebands of a composed line during transfer to casting position, the front side wall of said structure including a fixed lower section and a detachable upper section, means carried by the upper section for converting it into a hand stick when detached, and means for locating the said section in the proper position relative to the rear side wall when it is applied to the machine.

13. A channel structure as specified in claim 80 12, including latch pins for locking the said removable section in place, banking screws for sustaining the section in a truly vertical position, and a spring for holding it resiliently engaged with said screws.

14. In or for a typographical casting machine 85 adapted to handle matrices and expandible spacebands formed with projecting ears, a channel structure comprising an integral rear side wall formed with horizontal rails, and a front side wall made up of a fixed lower section and a detachable upper section formed with horizontal rails corresponding to those of the rear wall and serving in conjunction therewith to support the 90 matrices and spacebands by their projecting ears, said upper section being provided with a pair of line confining fingers movable to active and inactive position and with a retaining bar likewise movable to active and inactive position, whereby said upper section may be converted into a hand 100 stick when detached.

15. In a typographical casting machine, the combination of a line transporter, and a matrix 105 guide channel arranged for alignment therewith, one wall of said channel being removable at will and useable as a hand stick for the composition of a line of matrices therein.

16. In a typographical casting machine, the combination of a line transporter, and a matrix 110 guide channel arranged for alignment therewith, 115 and having rails formed on its opposite walls for supporting matrices therein by their projecting ears, one wall of said channel being removable at will and useable as a hand stick for the composition of a line of matrices therein.

17. In a typographical casting machine, the combination of a line transporter, and a matrix 120 guide channel arranged for alignment therewith, one wall of said channel being removable at will and useable as a hand stick for the composition 125 of a line of matrices therein, and said wall being equipped with means to hold the composed line in place thereon while it is removed from the machine.

18. In a typographical casting machine, the combination of a line transporter, and a matrix 130 guide channel arranged for alignment therewith, one wall of the channel being removable at will and useable as a hand stick for the composition of a line of matrices therein, and said 135 wall being provided with a bar pivotally mounted thereon and adapted to be held in engagement with the line of matrices to prevent lateral displacement thereof, and a pair of fingers pivotally attached to the opposite ends of said bar and adapted to form end abutments for the composed line of matrices.

19. In a linotype machine, the combination of the vertically movable first elevator, the vertically 140 movable assembling elevator, and the stationary intermediate channel arranged to align with the first elevator when the latter is in its normal position of rest and to align with the assembling elevator when the latter is in its up- 145 150

permest or line transfer position, whereby a line of machine-composed matrices may be transferred from the assembling elevator into the first elevator through the intermediate channel, 5 said intermediate channel being characterized by the fact that its front wall is removable to permit the composition by hand of a line of matrices therein and is thereafter replaceable to permit the transfer of such hand-composed 10 line into the first elevator.

tory to their delivery to the casting mechanism, of a typographical machine, which consists in removing a section of a given organ of the machine normally arranged to handle machine-composed matrices, composing a line of the matrices by hand in said section, and then restoring the section to its original place in said organ so as to locate the matrix line in the proper position for delivery.
